UNITED STATES PATENT OFFICE.

JOHN KARMAZIN, OF DETROIT, MICHIGAN.

CONDENSER.

Application filed May 31, 1924. Serial No. 716,942.

This invention relates to an improvement in the construction of radiators for internal combustion engines or the like and in particular to a means for preventing loss of the cooling fluid therein through evaporation during the normal operation of the engine.

Radiators for automotive internal combustion engines are normally constructed with an overflow or vent tube leading from a point near the top or filling neck of the radiator to a point near the bottom of the radiator where it is adapted to discharge outside the radiator the cooling fluid which overflows into the overflow tube due to over filling of the radiator or expansion of the fluid by heat.

This overflow or vent tube is always open and during the normal operation of the engine a small amount of steam or vapor is continuously formed from the cooling fluid and escapes through the drainage tube so that there is a continual loss of the fluid which necessitates frequent refilling of the radiator.

It is an object of the present invention to provide a means for preventing the escape of these vapors under normal operating conditions so that they will be retained in the radiator and condensed and returned to the cooling fluid, but which will permit the escape thereof when the pressure of the vapors exceeds a predetermined maximum.

Another object of the invention is to provide a condenser of the kind described which is simple to construct, unlikely to get out of order and may be used without interfering in any way with the normal operation of the radiator.

Another object of the invention is to provide a condenser of the kind described, which may be formed as a part of the radiator cap and which may be carried by the radiator cap and concealed in the filling neck of the radiator but which will not interfere in any way with the filling of the radiator.

Another object of the invention is to provide a condenser of the type described which will automatically indicate to the driver of the automobile or the operator of the engine when the pressure exceeds the predetermined maximum and that a condition of danger is imminent.

Various other objects and advantages will occur as the description of the invention proceeds.

Referring now to the drawings, which illustrate one form of embodiment of the invention,

Figure 1 is a sectional view of one embodiment of my condenser positioned in the filling neck of the radiator.

Figure 2 is a sectional view on the line 2—2 of Figure 1.

Figure 3 is a view showing the operation of the automatic signaling device.

Figure 4 is a sectional view of a modified form of condenser.

In the embodiment illustrated the condenser 1 is shown as being mounted in the filling neck 2 of the radiator 3 and formed as part of the radiator cap 4, but it is to be understood that the condenser could be placed in any other position on the radiator, it being only necessary that when the condenser valve 5 is opened communication is established between the radiator 3 and the overflow tube 6.

When the condenser is positioned in the filling necks, as illustrated, the neck 2 is provided with a ledge 7 through which drainage tube 6 projects into the filling neck, and the cap 4 is provided with a tube like projection 8 adapted to seat upon the ledge 7, when the cap is screwed into the filling neck, to form a fluid tight joint therewith.

Inside the projection 8 there is a tubular boss 9 adapted to receive and guide the stem 10 of the valve 5 which seats on the seat 12 in the lower end of the projection 8. A coil spring 13 is positioned on the outside of the boss 9 and urges the valve 5 toward its seat 12. A plurality of holes 14 permits communication between the inside of tubular projection 8 and the space 15 in the filling neck above the ledge 7.

If desired the hole 16 may be made in the top of the cap 4 and a tubular valve stem 10 be used, so as to permit the tube 17 of an ordinary temperature indicator or thermometer 18 to project into or through the condenser to contact with the steam in the radiator, to indicate the temperature of the cooling fluid.

In the operation of the condenser, the cap 4 and condenser are removed by unscrewing the cap 4 as in the ordinary radiator, the radiator is filled through the hole 19 in the ledge 7 and the cap screwed back in place to seat the bottom of the projection 8 on the ledge 7. In the normal operation of the radiator the vapor which forms from the heated fluid rises to the top of the radiator and finding no escape it is condensed on reaching the cooler top portion of the radiator or upon stopping of the engine and returned to the

fluid in the radiator. When however an excessive amount of vapor is formed so that the pressure in the radiator exceeds the strength of the spring 13 the valve 5 is lifted from its seat 12 and the vapor or fluid escapes through the hole 19 into the tubular projection 8 and thence through the holes 14 and drainage tube 6 to the outside of the radiator. When the pressure is reduced to the desired amount 10 the valve 5 is again seated and the condensing of the vapors resumed.

Figure 4 illustrates a slightly modified form of construction, in which the overflow tube 6 is extended by the passage 6^a to a point 15 adjacent the top of the filling neck 2^a where it communicates with a groove 28 around the top of the filling neck. The cap 4^a is provided with a tubular projection 29 closed at its lower end by a plug 30 which forms the seat 20 31 for the spring pressed valve 5^a constructed as described in connection with Figure 1. A plurality of holes 32 extend through the walls 25 of the tubular projection 29 and communicate with the groove 28 to permit the escape 30 of steam and water through the tube 6 when the valve 5^a is opened by excess pressure in the radiator. The top of the filling neck 2^a and the cap 4^a are screw threaded to permit screwing of the cap in place as in the usual construction.

In the modification shown in Figure 3 the valve stem 10 has connected therewith a lever 20 which projects through the cap 4 into the casing for the indicator 21. A signal device 25 22 which may comprise a pair of different colored discs 23 and 23^a mounted on a pivot 24 is arranged to be operated by the lifting of the valve 5 off its seat, to move the disc 23 from the window 25 and show the disc 23^a at 40 the window 25^a to give any appropriate warning signal to the driver that an excessive amount of steam is being formed in his radiator so that if the danger signal persists after the valve 5 is first opened he may investigate 45 the cause of the trouble.

In the particular embodiment illustrated the end of the lever 20 travels in an inclined slot 26 in the connecting member 27 for the discs 23 and 23^a so that the lifting of the 50 valve stem elevates the disc 23^a and lowers the disc 23 and vice versa, it is to be understood however that any appropriate signal other than that shown may be used to indicate the lifting of the valve 5 from the excessive steam in the radiator.

While the invention has been described largely with the view that water is the cooling fluid normally used and that steam is the vapor to be condensed, it will be obvious that the invention is especially valuable in preventing the loss of the alcohol where alcohol is used to prevent freezing in winter and for the condensing of vapors from any other cooling fluid.

65 In compliance with the patent statutes I

have illustrated and described the preferred embodiment of my invention but is to be understood that various modifications and changes can be made therein without departing from the spirit of the invention or scope 70 of the claims and that parts of the invention may be used without others.

I claim:

1. In an internal combustion engine radiator, a water chamber, a filling neck therefor, a ledge in said filling neck, an overflow tube projecting through said ledge and into said filling neck, a cap for said filling neck, a tubular projection on said cap adapted to form a fluid tight seal with said ledge, a valve in 75 said projection, a spring normally holding the valve closed and a plurality of holes through the walls of said projection to permit fluid to flow from the water chamber through the same into the overflow tube when the valve is open.

2. In an internal combustion engine radiator, a water chamber, a filling neck therefor, a ledge in said filling neck, an overflow tube projecting through said ledge and into said filling neck, a cap for said filling neck, a tubular projection on said cap adapted to form a fluid tight seal with said ledge, to prevent communication between the water chamber and the overflow tube, a valve in said projection, a spring normally holding the valve closed, a plurality of holes through the walls of said projection to permit fluid to flow from the water chamber through the same into the overflow tube when the valve is open, and 90 means projecting through the cap for indicating when the valve is open.

3. The combination with an internal combustion engine radiator comprising a fluid chamber and an overflow tube, of means normally preventing the escape of fluid from 100 said chamber to said overflow tube but adapted to permit such escape when the pressure in said fluid chamber exceeds a predetermined maximum, and means to indicate when the fluid is escaping.

4. The combination with the radiator of an internal combustion engine of a valve to normally prevent the escape of fluid, but adapted to open when the pressure in the radiator exceeds a predetermined maximum and discharge the fluid beneath the radiator and visible means to indicate when the valve is open.

5. In an internal combustion engine radiator, a water chamber, a filling neck therefor, a ledge in said filling neck, an overflow tube projecting through said ledge and into said filling neck, a cap for said filling neck, a tubular projection on said cap adapted to form a fluid tight seal with said ledge, a valve in 120 said projection, a spring normally holding the valve closed, a plurality of holes through the walls of said projection to permit fluid to flow from the water chamber through the same into the overflow tube when the valve is open.

same into the overflow tube when the valve is open, and visible means to indicate to the driver when the valve is open.

6. In an internal combustion engine radiator, a water chamber, a filling neck therefor, a ledge in said filling neck, an overflow tube projecting through said ledge and into said filling neck, a cap for said filling neck, a tubular projection on said cap adapted to form a fluid tight seal with said ledge, a valve in said projection, a spring normally holding

the valve closed, a plurality of holes through the walls of said projection to permit fluid to flow from the water chamber through the same into the overflow tube when the valve is open, and a visible signal operated by the opening of the valve to indicate to the driver that the pressure in the radiator exceeds the predetermined maximum.

In testimony whereof I have affixed my signature to this specification.

JOHN KARMAZIN.
